(57) **CLAIM**

The ornamental design for a combined primary and secondary lamp, as shown and described.

DESCRIPTION

FIG. 1 is a perspective view of a combined primary and secondary lamp showing my new design;

FIG. 2 is a front view thereof;

FIG. 3 is a back view thereof;

FIG. 4 is a left view thereof;

FIG. 5 is a right view thereof;

FIG. 6 is an enlarged top view thereof;

FIG. 7 is an enlarged bottom view thereof;

FIG. 8 is an enlarged detail view of area 8 of FIG. 1;

FIG. 9 is an enlarged detail view of area 9 of FIG. 2;

FIG. 10 is an enlarged detail view of area 10 of FIG. 2;

FIG. 11 is an enlarged detail view of area 11 of FIG. 2;

FIG. 12 is an enlarged detail view of area 12 of FIG. 3;

FIG. 13 is an enlarged detail view of area 13 of FIG. 4; and,

FIG. 14 is an enlarged detail view of area 14 of FIG. 5.

The dash-dash broken lines shown in the drawings depict portions of the combined primary and secondary lamp that form no part of the claimed design. The dot-dash broken lines depict the boundaries of the enlarged detail views and form no part of the claimed design.

1 Claim, 12 Drawing Sheets
